DEFROSTER CIRCUIT

Benjamin D. Thomas, Cincinnati, Ohio, assignor
to Avco Manufacturing Corporation, Cincinnati, Ohio, a corporation of Delaware

Application June 20, 1950, Serial No. 169,195

2 Claims. (Cl. 62—4)

1

This invention relates to defrosting refrigerator evaporators and is particularly applicable to defrosting the evaporators of electrically operated refrigerators of the household type. Various methods and means have heretofore been provided to eliminate the coating of frost that accumulates on the evaporator of such refrigerators during extended operation thereof, particularly where ambient conditions of high humidity exist. In some areas this high humidity condition exists for a considerable period of time and when it is accompanied by high ambient temperatures the problem of the accumulation of frost is a severe one. This is accentuated in cases where a large primary evaporator is relied upon for producing food preservation temperatures in the food compartment and low freezing temperatures in the freezing compartment.

Previous attempts to solve this problem have only been partially successful since they have required costly modification of standard refrigeration systems and controls or have not been capable of functioning with sufficient rapidity to melt the surface coating of ice or frost on the evaporator without likewise melting or unduly raising the temperature of frozen food stored in or on the evaporator.

The present invention overcomes these difficulties and permits the defrosting of a refrigerator evaporator by the rapid and uniform application of heat derived from an electric resistance element disposed upon or adjacent the areas of an evaporator where the frost accumulation is normally the most severe.

The invention contemplates the provision of heating means which is readily separable from the evaporator surfaces from which frost accumulation is sought to be removed, in order to render such heating means accessible for cleaning, repair or replacement.

An object of the invention is the provision of an electric circuit and control therefor which will insure the periodic defrosting of a refrigerator evaporator automatically.

Another object of the invention is to provide a defrosting device wholly independent of and separate from the hermetically sealed systems employed to provide refrigeration.

Another object of the invention is to provide an electrically actuated defrosting means in conjunction with an operating and control circuit which produces the desired result with certainty and rapidity and at the same time in an extremely simple and inexpensive manner.

A further object is to provide an electric circuit containing a series of safety devices which operate consecutively in order to insure against

2

the application of excessive heat to the evaporator of a refrigerator.

A further object is to provide a defrosting device which restricts the heat required for melting the frost to the outer areas of the evaporator, whereby undue elevation of temperature within the evaporator is avoided and frozen foods stored therein are unaffected.

A still further object is to provide a defrosting heater which is unitary in construction and which is unaffected by ice, moisture or washing solutions.

A still further object is to provide a control for a defroster circuit which avoids the use of relays within the electrical system and of shut-off valves within the refrigeration system.

The novel features that I consider characteristic of my invention are set forth in the appended claims. The invention itself, however,

both as to its organization and its method of operation, together with additional objects and advantages thereof, will best be understood from the following description of a specific embodiment when read in conjunction with the accompanying drawing, in which Fig. 1 illustrates a circuit according to the invention as applied to the refrigerant evaporator of an electrically operated refrigerating apparatus and Fig. 2 shows an enlarged, fragmentary section taken along line 2—2 of Fig. 1.

The invention is applicable to refrigeration systems of various types but in the illustrative embodiment it is shown as applied to a system in which a refrigerant compressor preferably

sealed in a dome supplies a suitable refrigerant gas such as dichlorodifluoromethane to a condenser wherein it is liquefied and supplied through suitable flow control means to an evaporator where the liquid refrigerant evaporates and absorbs heat in conventional fashion from the confined space, and the heat laden refrigerant vapor is carried out through a suitable suction tube and brought back into a low pressure space within or adjacent the compressor.

This system is conventional and is well understood in the art. The motor compressor 15, controlled by a starting relay 14, condenser 18, flow control device 21, evaporator 20, together with their connecting lines, constitute the principal instrumentalities of such a system and are shown more or less diagrammatically in the drawing.

In the apparatus of the present invention power is provided for the motor of the compressor through power lines 10 and 11 of a 110-120 volt A. C. line. In circuit with the power line 11 and starting relay 14 of the motor-compressor 15 is a timer or clock-operated switch 12

and a conventional temperature control 13 having movable contact G and fixed contact H. Control 13 is actuated by a conventional bulb 13a mounted in heat exchange relationship with evaporator 20. A rise of temperature in evaporator 20 increases the pressure in bulb 13a and this pressure rise is transmitted through tube 13b to a Sylphon bellows in 13, the movement of which causes movable element G to make contact at H. This control is well known in the art and will not be described in detail.

The line 11 is connected to the movable element A of timer 12 and fixed element C thereof is connected to the movable element G of thermostat 13. The other side of the starting relay is connected through conduit 14A to line 10 and to a heating element consisting of a straight continuous length 29 and a sinuous length 29a of tubular element having a high resistance, secured to the evaporator 20. A similar heating element 30, 30a is connected through line 17a to fixed contact E of a temperature responsive device 16 through a safety device 17 such as a thermostatic control device responsive to excessive heat or current or both, disposed in heat exchange relationship with evaporator 20 and the heaters.

The temperature sensitive device 16 comprises a temperature sensitive switch having a control bulb 16a disposed adjacent the evaporator. The movable element D of the switch is connected to the fixed element B of the timer 12. The other fixed element F of switch 16 is connected to the fixed element C of timer 12. The heaters 29-30 are preferably tubular, constructed of nickel chromium alloy wire sealed in a heat conductive tube but insulated therefrom with a refractory material such as magnesium oxide.

The heaters are advantageously formed so that they lie between or adjacent the refrigerant-containing passages 22, 24 in evaporator 20. The construction shown may be varied somewhat and the heaters may be mounted otherwise than as shown and may have courses extended over the side and back of the evaporator 20 depending upon the defrosting requirements of the evaporator design. It is desirable that the heaters be secured to the primary refrigerating surfaces, i. e., those in which the evaporator passages are contained or to which they are secured.

In order to supply heat to the back plate 56 by conduction, the heater may conveniently be attached to the evaporator by extensions 56a integral with or secured to plate 56 so that they clamp against course 29 of the heater (see Fig. 2). Similar means 55, 57, 58, 59 and 60 are provided for holding the heaters with respect to the end plates 52 and 53 and the bottom plate 51 and conducting heat thereto. Clamping means 61 and 62 are provided for holding the front edges of the heaters to the top plate 50 and bottom plate 51.

As will be noted, the evaporator 20 is closed at the sides and back, and it is also closed at the front by an access door (not shown) provided with suitable gaskets for sealing the interior so that it is not subject to the air currents which pass through the food compartment and over the external surfaces of evaporator 20. It is important to prevent the accumulation of frost on the interior surface of evaporator 20.

In the illustrative embodiment, the refrigerant is supplied from compressor 15, and it successively passes through conduit 21a, condenser 18, flow control device 21, and circuitous passage 22 in the bottom plate of the evaporator. From the

end of this passage the refrigerant flows through a connecting passage to another circuitous passage 24 at the top of the evaporator at the end of which is provided a header 26 from which refrigerant gas is removed through the suction tube 27 and drawn into the suction side of the compressor at 27a.

The timer 12 is a clock-operated mechanism which by the use of mercury or snap acting switches permits the rapid making and breaking of electrical circuits carrying a considerable amount of current. Its setting is adjustable and is preferably set to make contact at A and B every twenty-four hours, at a time when the refrigerator will not likely be in use.

In operation the clock-operated switch is set so the circuit to the compressor is made from line 11 through movable contact A and fixed contact C, and normally closed temperature control contacts G and H. When the circuit is in this condition the compressor cycles normally through the temperature responsive element 13 which, as above indicated, is responsive to temperatures of the evaporator or the food storage compartment, for instance, through bulb 13a. When the temperature has risen to a degree determined by the setting of the thermostat 13, movable contact G moves away from fixed contact H and opens the motor-compressor circuit thus described.

The timer is set to permit periodic defrosting, as above indicated. When so set, the time clock starts the defrosting operation by breaking the contacts A and C and making contacts A and B. This stops the compressor, if the motor circuit is not already broken at G-H, and applies power to the heaters 29, 29a, 30, 30a, through circuit 11, A, B, movable contact D of the defrost thermostat 16, fixed contact E of the defrost thermostat 16, 17a, 17, 30, 30a, 29a, 29 and 10. Element 28 is simply a jumper for conveniently connecting the heaters in series.

The temperature responsive device 16 is so adjusted and related to the evaporator 20 and the heaters 29 and 30 that it will break the contacts D and E and make contacts D and F when the temperature has risen to a point at which adequate defrosting has been completed. The output of the heaters is designed so that this occurs in a relatively short time, say five to ten minutes, and in any event a time insufficient to deleteriously affect the frozen foodstuffs or ice cubes within the evaporator. The making of contacts D and F reappplies power to the compressor through a by-pass circuit as follows: 11, A, B, D, F, C, G, H, 14, 14a and 10.

It is important to set the time clock to break contacts A and B and reestablish A and C a short time period after the time when defrost thermostat 16 is calculated to have established connection between contacts D and F. This provides a safety feature which insures against the possibility that the defrost thermostat 16 might not operate. Accordingly, even though the latter does not open the heater circuit at D and E, the circuit is broken at A and B, and the compressor circuit reestablished through A and C.

A still further protective device is provided by a second thermostat 17 which is sensitive to an elevation of temperature in an area closely adjacent the evaporator 20 and heaters 29 and 30. Device 17 may also be made sensitive to excessive current. In either case device 17 is arranged so that, if it feels a predetermined elevation in temperature or an excessive current flow, for instance by reason of the failure of the heater

thermostat 16 and the timer 12, it effectively breaks the heater circuit. For convenience of disclosure, thermostat 17 is shown adjacent and alongside of evaporator 20. In actual practice, however, it is desirable to place this thermostat in the upper portion of the refrigerator cabinet and it may be depressed in a cavity within the insulation, and closely adjacent the inner liner thereof.

It is obvious that the application of heat to the evaporator for more than the relatively short time required to defrost it would not be advantageous both from the point of view of possible spoilage of frozen foods stored therein and of possible damage to the refrigeration system by supplying heat thereto in an amount more than that which it is designed to accommodate. The controls provided by the present invention and their relationship to the operation of the system are adequate to insure against these contingencies and provide a series of safety devices operating consecutively, in effect, a triple safety device. These controls, however, are extremely simple in their construction and assembly, and the difficulties and risks involved in the use of valves in the refrigeration system and relays in the electrical or control system are avoided as well as the cost thereof.

The precise adjustment of timer 12 and thermostats 16 and 17 will depend of course on a number of factors including the size and capacity of the evaporator and the amount of frost calculated to have accumulated thereon during the previous period during which refrigeration has occurred. I have found, however, that a defrosting system may be constructed in accordance with the principles of the invention by using the following equipment under the conditions noted:

Compressor 15: $\frac{1}{8}$ H. P. of the reciprocating type.

Evaporator 20: Horizontal frozen food type constructed of 13" x 22" refrigerated top and bottom plates joined into a box section with 8" aluminum back and side panels, the whole comprising approximately 1½ cu. ft. of volume and 6½" sq. ft. external surface area.

Condenser 18: Tube and fin construction of such design as to give efficient operation with the above evaporator and compressor at zero degrees to 10 degrees F. at normal control setting.

Cabinet size: 9 cu. ft. of refrigerated space. Cabinet construction conventional including outer shell and inner liner, breaker strip, door outer shell, door inner liner, insulation approximately 3½" of glass or rock wool.

Defrosting heaters, 29, 30: Tubular heaters of conventional resistance wire surrounded by refractory oxides such as magnesium oxide in turn surrounded by a nickel plated copper sheath having a diameter of approximately ¼".

Heater for top evaporator plate: 300 watts, length approximately 105 inches.

Heater for bottom evaporator plate: 500 watts, length approximately 100 inches.

Defrost thermostat 16: Vapor filled construction, single pole, double throw operation, high temperature contacts made at approximately 50°; low temperature contacts made at approximately 20° F.

Safety thermostat 17: Conventional bimetallic single pole, single throw construction mounted at top of cabinet liner and opening at temperature indicative of over-heating operation (80-90° F.).

Time switch 12: Self-starting synchronous

motor operating cams to actuate a single pole, double throw snap switch every twenty-four hours maintaining one set of contacts approximately twenty minutes and the other set for the remainder of the twenty-four hour period.

Having thus described my invention, I claim:

1. In an electrical refrigerator of the type energized by two supply mains and comprising a compressor motor and an evaporator, a defrosting device comprising, in combination: a connection from one supply main to said motor, an electric heater disposed adjacent said evaporator, a connection from said one supply main to said heater, a timing device, a first single-pole, double-throw circuit selector having a movable contact connected to the other supply line, said first selector being actuated by said timer to stop the motor by circuit breaking and to energize the heater by circuit making when defrosting is initiated, said selector including a first fixed contact in circuit with said motor and a second fixed contact, a thermostat disposed adjacent to said evaporator, a second single-pole, double-throw circuit selector having a movable contact connected to said second fixed contact, said second selector being actuated by said thermostat to de-energize the heater by circuit breaking to restart said motor by circuit making when defrosting is completed, said second selector including a third fixed contact in circuit with said heater and a fourth fixed contact in a conductive path with said first fixed contact, and means coupling the first circuit selector to said timer for reactivation by said timer to assure restarting of said motor by circuit making and de-energizing of the heater by circuit breaking at the end of a predetermined interval.

2. In an electric refrigerator of the type comprising an evaporator, a heater element and a compressor motor for circulating refrigerant, the combination of clock-actuated means having two positions for alternatively energizing the motor or conditioning the heater for energization, a thermostat, thermostat-actuated means, operable when the heater is conditioned for energization, for alternatively assuring the energizing of said motor or the energizing of said heater, said thermostat-actuated means comprising a selector, said selector comprising a movable contact actuated by the thermostat and two spaced fixed contacts, a motor energizing circuit for said compressor motor which is closed when said movable contact engages one of said fixed contacts, and a heater energizing circuit which is closed when said movable contact engages the other of said fixed contacts.
